SNOW MACHINE CARRIER

Richard H. Camp, Box 62, Haines, Oreg. 97833

Filed Feb. 19, 1970, Ser. No. 21,601

Term of patent 14 years

Int. Cl. D12—14

U.S. Cl. D14—24

FIG. 1

FIG. 2

FIG. 3

FIG. 1 is a left rear perspective view of the snow machine carrier embodying my new design with a snow machine shown in dotted lines for illustrative purposes only;

FIG. 2 is a left front perspective view; and

FIG. 3 is a right rear perspective view as viewed from the bottom.

I claim:

The ornamental design for a snow machine carrier, substantially as shown and described.
